SINGLE UNIT FULL-FASHIONED STOCKING

Joseph L. Beers, Bloomfield, N. J., assignor to
Julius Kayser & Co., Brooklyn, N. Y.

Application April 21, 1938, Serial No. 203,252

34 Claims. (Cl. 66—187)

The present invention relates to hosiery, more particularly to full-fashioned stockings of the single unit type, the present application being a continuation in part of my co-pending application, Serial Number 106,828, filed October 21, 1936.

As known in the art, the manufacture of the ordinary type of full-fashioned stocking blanks requires the use of two distinct and separate machines—one called the "legger" and the other known as the "footer." The legger is adapted to knit the leg portion of the stocking blank, including the heel tabs, while the footer is devised to knit the foot (consisting of the instep, sole, and toe) of the blank as a continuation of the leg and heel tabs after said leg and heel tabs have been transferred onto the needles of the footer.

The manufacture of full-fashioned stockings of the single unit type differs from the manufacture of the ordinary type in that the leg and foot of the blank of a single unit type of stocking are knitted continuously on one and the same machine.

Full-fashioned stockings of the single unit type are preferable to the ordinary type because, due to the fact that the leg and foot portions are knitted contiguously, there are produced a proper matching between the leg and foot fabric, and uniform texture throughout the blank. However, the manufacture of single unit type of stockings has heretofore been limited and practically prohibited because the various methods devised for their manufacture are quite involved and necessitate the utilization of complicated machines which, obviously, places the cost of production on an exceedingly high scale.

The present invention particularly aims to provide a single unit full-fashioned stocking wherein the leg and foot fabric portions are integrally knitted from continuous lengths of yarn, thereby producing perfection and uniformity of matching and texture throughout the entire sheer portion of the stocking, and wherein the heel fabric portion is knitted from yarns separate of the body yarn as a continuation of the leg fabric portion, and interknitted with the foot fabric portion, whereby the leg, heel, and foot are continuously and integrally combined to present a unitary knit structure.

It is an important feature of the invention to provide a single unit full-fashioned stocking of the character mentioned, wherein the combination leg and foot blank and the heel tabs are interconnected directly on a knitting machine

5 by knitting the heel tabs as continuations of the leg portion of the blank, and during the knitting of said heel tabs, interknitting in overlapping relation therewith the sole portions of the blank, thus eliminating the usual looping or sewing operation and producing a flat and firm connecting seam between the various adjacent associated fabrics.

Other important objects and advantages of the invention will be in part obvious and in part pointed out hereinafter.

In order that the invention and its mode of operation may be readily understood by those skilled in the art, I have, in the accompanying drawings and in the detailed description based thereupon, set out possible embodiments of the same. In these drawings:

Figure 1 is a face elevation of a single unit full-fashioned stocking blank constructed in accordance with the invention and having heel tabs incorporated therein.

Figure 1A is a side elevation of a finished stocking made from a blank such as that shown in Figure 1.

Figure 2 illustrates the stocking blank including the leg and foot portions continuously knitted to form the single unit blank.

Figure 3 diagrammatically shows a portion of the blank severed and folded for topping onto the 30 needles of a knitting machine for knitting heel tabs onto the blank.

Figure 4 diagrammatically illustrates the portion of the blank shown in Figure 3 at the completion of the heel tabs.

Figure 5 is an enlarged detail of the blank diagrammatically illustrating the formation of the severing courses.

Figure 6 shows the portion of the blank illustrated in Figure 5 with a part of a heel tab integrally knitted therewith.

Figure 7 diagrammatically shows the engagement of the loops with sets of knitting and non-knitting needles.

Figures 8, 9, and 10 diagrammatically illustrate 45 various modifications in the transfer of the loops in the foot portion for interlooping engagement with the heel tabs as the knitting thereof progresses.

Having more particular reference to the drawings, wherein like characters of reference will designate corresponding parts throughout, I have shown in Figure 1 the complete stocking blank including the welt 2, the leg 3, the high splice heel sections 4, the heel tabs 5, the instep 6, the sole sections 7, and the toe 8. In accordance

with the invention, the leg 3, the high splice heel sections 4, sole sections 7, and toe 8 are knitted integrally from continuous lengths of yarn A on one machine. The high splice heel sections 4, together with the sole sections 7 and toe 8 may be reinforced by introducing additional yarns B in the usual manner. There is thus produced a single unit full-fashioned leg and foot blank of the type more clearly illustrated in Figure 2.

As shown in said Figure 2, at the point where the high splice heel sections 4 of the leg 3, and the sole sections 7 of the foot, where the blank is to be severed for the insertion of heel tabs by means of a knitting machine of the type shown and described in my co-pending application, Serial Number 139,129, filed April 27, 1937, there are knitted series of partial loose courses 10 which extend from the selvedge edges for a predetermined distance into the body of the blank, the length of the partial courses depending upon the desired width of the heel tabs to be inserted in the fabric.

The provision of the partial loose courses 10, it will be understood, affords a convenient guiding line for the severing of the fabric and, for that purpose, the feed of the additional reinforced yarns B is preferably stopped during the formation of said partial loose courses as is more clearly shown in Figure 5.

Subsequent to the separation of the fabric, as stated, the foot portion is folded over the leg portion, and the sole sections 7 are folded upon the instep section 6 in the manner more clearly represented in Figure 3 of the drawings. By folding the stocking blank in the manner specified, it will be appreciated that the marginal rows of loops 12 of the high splice heel sections 4, and the marginal rows of loops 13 of the sole sections 7 lay substantially on a straight line, as indicated at 14, so that said rows of loops 12 and 13 may be topped on the bank of needles of a footer converted to knit the heel tabs.

It is to be noted that because of the folding of the blank, as above set forth, the loops of the foot and sole sections are reversed so that, in the topping operation, the sinker portion of the marginal row of loops 13 of each sole section 7 will engage the corresponding needles of the converted footer, whereas the needle portion of the marginal row of loops 12 of each high splice heel section 4 will engage the associated needles of said footer in the manner more clearly represented in Figure 7 of the drawings.

The converted footer is provided with two sets of needles, diagrammatically shown in Figures 7, 8, 9, and 10, one set of needles 15 being non-knitting needles, the other set of needles 16 being adapted to knit in the usual way so that the heel tabs 5 may be knitted as continuations of the high heel sections 4.

As shown, the non-knitting needles 15 preferably consist of needles having shortened beards, which prevent the loops 13 on said needles from being pressed off during the knitting of the heel tabs 5. It is also possible to use ordinary knitting needles, instead of the shortened beard needles and, in this event, the usual presser edge, which is disposed opposite said needles, may be removed so that the needles will not press off, or the needles may be so mounted as to be moved away from their associated presser edge, which will likewise prevent pressing off.

For the knitting of the heel tabs 5, there are fed to the knitting needles 16 reinforced yarns C which are separate from the continuous

lengths of body yarn A and from the high heel and sole reinforced yarns B.

Associated with the non-knitting needles 15 are transfer points 17 devised to pick the loops 13 off said non-knitting needles 15 and transfer them for interlooping engagement with the adjacent wale loops of the heel tabs 5 as the same are being knitted.

The loops 13 on the non-knitting needles 15 are transferred the distance of one or more wales, as necessity or preference may dictate. In Figure 8, I have illustrated the single wale transfer. According to this mode of operation of knitting the heel tabs 5 and simultaneously joining the sole portions 7 thereto, the transfer points 17 descend and pick all the loops 13 off the non-knitting needles 15 and transfer said loops one needle distance, which places each end loop successively in engagement with the adjacent end knitting needle of the row of needles 16. One or more intermediate courses may be knitted on needles 16 between each transfer operation to provide the necessary fabric for the formation of the heel and to insure sufficient elasticity in the foot. This operation is repeated until all the loops 13 on the non-knitting needles 15 have been transferred the distance of one needle at a time, and interknitted to form a seam 21 uniting the sole portions 7 to the heel tabs 5.

In Figure 9, I have illustrated the two wale distance transfer. As shown, the transfer points 17 move the distance of two needles after having picked the loops 13 off the needles 15. It will be appreciated that since the two needle transfer, as compared with the single needle transfer, cuts in half the number of "dips" required to transfer the number of loops topped on the non-knitting needles 15, the two needle transfer operation will speed production in interknitting the loops in the manner heretofore described. However, at least three extra courses are found necessary after each interknitting course, to give the proper length to the heel, resulting in producing small openings at the line of juncture between the sole and the heel.

The defect above mentioned can be overcome by following the method of operation shown in Figure 10. In practicing this latter mode of operation, two sets of transfer points 22 and 23 are provided on the knitting machine. The transfer points 22 and 23 are adapted to simultaneously pick off the loops 13 and while points 23 are moved the distance of two needles, the points 22 (preferably two in number) are moved the distance of three needles. It will be understood that by proceeding in this manner, the first wale of the heel tabs 5 is left without transfer loops. While three extra courses are also required to be knitted between each transfer course, the holes which might result are not visible because the connections or joinings are all on the second and third wales of the tabs which are usually tighter and the first wale of the heel covers whatever small holes may result.

The transfer operation causes the marginal loops of the foot fabric to become interlooped with the adjacent marginal loops of the heel tab fabric and, accordingly, no seaming operation is necessary to unite the same. Furthermore, due to the transfer of the loops in the manner specified, the foot fabric is turned automatically at substantially right angles so that the finished blank assumes the proper shape to fit the foot of the wearer. After finishing the blank according to the method above described, the same may

be looped, seamed, dyed, and finished as is customary in the art to complete the stocking as shown in Figure 1A.

Referring particularly to the seam 21 formed on the knitting machine to unite the sole sections 7 to the heel tabs 5, it will be noted that the interknitted overlapping connection therebetween constitutes a flat and firm seam lacking the bulky and uneven appearance of a looped or sewed seam.

Moreover, because of the overlapping relation of the loops and their interknitted connection, the stresses to which said loops are usually subjected at the seam uniting the sole sections to the heel tabs of a stocking, are distributed uniformly along the entire line of connection thereby enhancing the appearance and wear-resisting qualities of the stocking.

Attention is directed to the fact that the sinker loops of the sole portion have an overlapping relationship with the associated needle loops of the heel portion, that is to say, the entire bight of the sole loop overlaps and lies upon the bight of a heel tab loop, and this can only be accomplished when the entire bight of the sole portion loop is lifted from the needle and transferred to another needle so that the entire bight of the sole portion loop and the entire bight of the heel tab loop both hang upon the one needle. After this has been accomplished, a needle loop of the heel tab is completely drawn through the overlapping bights of a sole sinker loop and a heel needle loop of the preceding course. Thus there is provided an overlapping interknit connection between the sole portion and the heel tab. The word "overlapping" as herein used defines the paralleling relationship between the bights of the sole and the heel fabric loops, and "interknit" as herein used defines the complete drawing of a loop through the overlapping bights to provide an interknit connection therebetween as shown in the drawings.

I wish it to be understood that the stocking construction and the method of forming the blank therefor may slightly vary without departing from the spirit of the invention. Accordingly, those modifications which come within the scope of the following claims are to be considered within the spirit of the invention.

What I claim is:

1. A stocking consisting of a combination leg fabric and foot fabric blank, and heel tabs knitted into said blank as a continuation of the leg fabric having selvedge needle loops drawn through and interknit with a row of sinker loops of the foot fabric to provide a knitted seam between the sole fabric and the heel fabric.

2. A full-fashioned stocking comprising a combination knitted leg fabric and knitted foot fabric blank including sole portions and heel tabs knitted into said blank as continuations of the leg fabric, rows of sinker loops of the sole portion of the foot fabric having an overlapping relationship with selvedge needle loops of the inner edges of the heel tabs, said selvedge needle loops drawn through said rows of sinker loops.

3. A knitted stocking comprising a leg portion, a sole portion, and a heel tab knitted to one of said portions, said sole portion having a course of sinker loops arranged in overlapping relationship with needle loops of the selvedge edge of the heel tab with certain needle loops of the heel tab drawn completely through said sinker loops for interknitting said loops in overlapping relationship.

4. A full-fashioned stocking comprising a leg fabric, a sole fabric, and an instep fabric, and heel tabs each knitted as a continuation of one of said fabrics, each of the heel tabs and one of said fabrics having rows of needle loops arranged in overlapping relationship with rows of sinker loops, with one of said rows of loops drawn completely through the other row of loops to interknit all the rows of loops in overlapping relationship.

5. A stocking blank comprising combined leg and foot fabrics knitted from continuous lengths of yarn, and heel tabs knitted from yarns separate from said lengths of yarn and each having a course of loops drawn through loops of a course in the leg fabric and a wale of loops drawn through loops of a course in the foot fabric.

6. A stocking comprising combined leg and foot fabrics knitted from continuous lengths of yarn, and heel tabs knitted from yarns separate from said lengths of yarn and each having a course of loops drawn through loops of a course in the leg fabric and a wale of loops drawn through loops of a course in the foot fabric.

7. A full-fashioned stocking comprising combined leg and foot fabrics knitted from continuous lengths of yarn, and heel tabs knitted from yarns separate from said lengths of yarn and each having a course of loops drawn through loops of a course in the leg fabric and a wale of loops drawn through loops of a course in the foot fabric.

8. A full-fashioned stocking blank comprising: combined leg and foot fabrics knitted from continuous lengths of yarn, and heel tabs knitted from yarns separate from said lengths of yarn as continuations of the leg fabric and having needle loops of their inner selvedges drawn through sinker loops of the foot fabric providing an integral overlapping interknit connection therebetween.

9. A full-fashioned stocking blank comprising: combined leg and foot fabrics knitted from continuous lengths of yarn, and heel tabs knitted from yarns separate from said lengths of yarn and having a plain interknit connection with the leg fabric and needle loops of their inner selvedges drawn through sinker loops of the foot fabric providing an integral overlapping interknit connection therebetween.

10. A full-fashioned stocking blank comprising: combined leg and foot fabrics knitted from continuous lengths of yarn and provided with reinforced high heel and sole sections, and heel tabs knitted from yarns separate from said lengths of yarn as continuations of the reinforced high heel sections and having needle loops of their inner selvedges drawn through sinker loops of the reinforced sole sections providing an integral interknit connection therebetween.

11. A full-fashioned stocking blank comprising: combined leg and foot fabrics knitted from continuous lengths of yarn and provided with reinforced high heel and sole sections, and heel tabs having a plain interknit connection with said reinforced high heel sections and needle loops of their inner selvedges drawn through sinker loops of said sole sections providing an integral overlapping interknit connection therebetween.

12. As an article of manufacture, a stocking comprising combined leg and foot fabric portions integrally knitted from continuous lengths of body yarn, and a heel fabric portion knitted from yarns separate from the body yarn, said

heel fabric portion having the needle loops of its first course drawn through the needle loops of the last course of the leg fabric portion, and having the needle loops of its inner selvedge portion drawn through the sinker loops of the first course of the foot fabric portion.

13. As an article of manufacture, a full-fashioned stocking comprising a combination leg and foot blank knitted from continuous lengths of body yarn said leg and foot blank having high heel and sole sections, and heel tabs each having the loops of its first course interknit with the loops of the last course of the corresponding high heel section, and the needle loops of its inner selvedge portion drawn through the sinker loops of the first course of the adjacent sole section of the blank.

14. As an article of manufacture, a full-fashioned stocking comprising combined leg and foot fabric portions integrally knitted from continuous lengths of body yarn, and a heel fabric portion knitted from yarns separate from the body yarn as a continuation of the leg fabric portion, said heel fabric portion having loops disposed in overlapping relation with loops of the foot fabric portion, and further having loops drawn through said overlapping loops to interknit the same.

15. As an article of manufacture, a full-fashioned stocking comprising a combination leg and foot blank knitted from continuous lengths of body yarn, said leg and foot blank having high heel and sole sections, and heel tabs knitted from yarns separate from the body yarn as continuations of the high heel sections of the blank, said heel tabs having loops disposed in overlapping relation with loops of the sole sections of said blank, and further having loops drawn through said overlapping loops to interknit the same.

16. A full-fashioned stocking blank comprising: combined leg and foot fabrics and heel tabs knitted as continuations of the leg fabric and having needle loops of their inner selvedges drawn through sinker loops of the foot fabric providing an integral overlapping interknit connection therebetween.

17. A full-fashioned stocking blank comprising: combined leg and foot fabrics provided with reinforced high heel and sole sections; and heel tabs knitted as continuations of the reinforced high heel sections and having needle loops of their inner selvedges drawn through sinker loops of the reinforced sole sections providing an integral interknit connection therebetween.

18. A stocking comprising a knitted foot fabric and a knitted heel fabric, one of said fabrics having certain loops disposed in overlapping relationship with certain loops of the other of said fabrics, and one of said fabrics having certain loops drawn through said overlapping loops of both fabrics to form an interknit connection therebetween.

19. A stocking comprising a knitted foot fabric and a knitted heel fabric, said foot fabric having certain loops disposed in overlapping relationship with certain loops in the heel fabric, and said heel fabric having certain loops drawn through said overlapping loops of the foot and heel fabrics to form an interknit connection therebetween.

20. A stocking comprising a knitted leg fabric, a knitted foot fabric, and a knitted heel fabric, said heel fabric having loops interknitted with loops of the leg fabric, said foot fabric having certain loops disposed in overlapping relationship with certain loops in the heel fabric, and said heel

fabric having certain loops drawn through said overlapping loops of the foot and heel fabrics to form an interknit connection therebetween.

21. In a stocking of the character described, a sole fabric and a heel fabric, one of said fabrics having a coursewise row of loops overlapping a walewise row of loops of the other of said fabrics, with predetermined loops of the walewise row of loops completely passing through and interlooping with said overlapping loops.

22. In a stocking of the character described, a sole fabric and a heel fabric, said sole fabric having a coursewise row of loops overlapping a walewise row of loops of the heel fabric, with predetermined loops of said walewise row of loops of the heel fabric completely passing through and interlooping with said overlapping loops.

23. A knitted fabric structure comprising a pair of adjoining knitted portions, one of said portions having a coursewise row of loops overlapping a walewise row of loops of the other of said portions with predetermined loops of the walewise row of loops completely passing through and interlooping with the overlapping loops.

24. A knitted fabric structure comprising a pair of adjoining knitted portions, one of said portions having certain loops disposed in overlapping relationship with certain loops of the other of said portions, and one of said portions having certain loops drawn through the overlapping loops of both portions to form an interknit connection therebetween.

25. A knitted fabric structure comprising a pair of adjoining knitted portions, one of said portions having loops disposed in overlapping relation with loops of the other of said portions and further having loops drawn through said overlapping loops.

26. A knitted fabric structure comprising a pair of adjoining knitted portions, one of said portions having needle loops drawn through and interknit with a row of sinker loops of the other of said portions to provide a knitted connection between the mentioned portions.

27. A knitted fabric structure comprising a pair of adjoining knitted portions, one of said portions having a row of selvedge loops, the other of said portions having loops overlapping certain selvedge loops of the first mentioned portion and said first mentioned portion having certain other selvedge loops drawn through the overlapping loops.

28. A knitted fabric structure comprising a pair of adjoining knitted portions, one of said portions having a row of selvedge loops, the other of said portions having a row of sinker loops overlapping certain selvedge loops of the first mentioned portion and said first mentioned portion having certain other selvedge loops drawn through the overlapping loops.

29. A knitted fabric structure comprising a pair of adjoining knitted portions and a knitted insert between said portions, said knitted insert having loops drawn through loops in one of said portions, loops disposed in overlapping relation with loops in the other of said portions, and loops drawn through and interlooped with the loops disposed in overlapping relation.

30. A knitted fabric structure comprising a pair of adjoining knitted portions and a knitted insert between said portions, said knitted insert having needle loops drawn through needle loops in one of said portions, needle loops disposed in overlapping relation with sinker loops in the other of said portions, and needle loops drawn through

and interlooped with the needle and sinker loops disposed in overlapping relation.

31. A knitted fabric structure comprising a pair of adjoining knitted portions and a knitted insert between said portions, said knitted insert having a coursewise row of loops drawn through a coursewise row of loops in one of said portions, a walewise row of loops disposed in overlapping relation with a coursewise row of loops in the other of said portions and certain loops of said walewise row of loops drawn through and interlooped with the loops disposed in overlapping relation.

32. A knitted fabric structure comprising a pair of adjoining knitted portions and a knitted insert between said portions, said knitted insert having a coursewise row of needle loops drawn through a coursewise row of needle loops in one of said portions, a walewise row of needle loops disposed in overlapping relation with a coursewise row of sinker loops in the other of said portions, and certain needle loops of said walewise row of needle loops drawn through and inter-

looped with the needle and sinker loops disposed in overlapping relation.

33. A knitted fabric structure comprising a pair of adjoining portions and a knitted insert between said portions, said knitted insert having a course of loops drawn through a course of loops in one of said portions and a wale of selvedge loops disposed in overlapping relation with a course of loops in the other of said portions, and certain loops of said wale of selvedge loops drawn through and interlooped with the loops disposed in overlapping relation.

34. A knitted fabric structure comprising a pair of adjoining portions and a knitted insert between said portions, said knitted insert having a course of needle loops drawn through a course of needle loops in one of said portions and a wale of selvedge needle loops disposed in overlapping relation with a course of sinker loops in the other of said portions, and certain needle loops of said wale of selvedge loops drawn through and interlooped with the needle and sinker loops disposed in overlapping relation.

JOSEPH L. BEERS.
